Robert B. Foley

BY H. G. Manning

ATTORNEY

UNITED STATES PATENT OFFICE.

ROBERT B. FOLEY, OF WATERBURY, CONNECTICUT.

ICE CREEPER.

Application filed June 22, 1925. Serial No. 38,703.

This invention relates to ice creepers, and more particularly to an ice creeper adapted to be detachably worn on the forward part of a shoe to permit the wearer to walk over the ice or other slippery surface, without danger of falling.

One object of the invention is to provide an ice creeper of the above nature which will be adjustable to fit shoes of various sizes.

A further object is to provide a device of the above nature which may be quickly and easily attached to and detached from a shoe.

A further object is to provide a device of the above nature which will be simple in construction, inexpensive to manufacture, easy to manipulate, and very efficient and durable in use.

With these and other objects in view, there has been illustrated on the accompanying drawings one form in which the invention may be conveniently embodied in practice.

Fig. 1 represents a top plan view of an ice creeper embodying the invention.

Fig. 2 is a side sectional view of the same, with parts broken away, showing the ice creeper in position ready to be clamped under a shoe sole.

Fig. 3 is a transverse sectional view of the ice creeper taken along the line 3—3 of Fig. 1.

Fig. 4 is a perspective view of the locking strip together with the clamping cam pivoted at one end thereof.

Fig. 5 is a perspective view of the body plate adapted to support the clamping members and locking strip.

Figs. 6 and 7 are perspective views of the left hand and right hand clamping members, respectively.

Referring now to the drawings in which like reference numerals denote corresponding parts throughout the several views, the numeral 10 indicates a shoe having a sole 11 adapted to be engaged by a pair of clamping members 12 and 13. The clamping members have their ends bent upwardly and inwardly to form jaws 14 and 15 respectively for engagement with the sides of the sole 11.

The jaw 14 is provided with a slot 16 adapted to form a guide for a locking strip 17, said locking strip 17 having two sets of oppositely disposed teeth 18 and 19, near one end thereof. The other end of said

locking strip has a cam member 19a pivoted thereto by a rivet 20, said cam member being preferably formed from a blank of thin sheet metal bent to form parallel upper and lower cam faces 21 which are adapted to lie above and below said locking strip. The free end 22 of the cam member 19 is U-shaped in cross section and serves as a handle, by means of which the cam member may be conveniently manipulated.

In order to form a rigid support for the clamping members 12 and 13 and the locking strip 17, provision is made of a body member 23, said body member comprising an elongated strip of sheet metal. The body member 23 is adapted to be held in guiding flanges 24 and 25 formed by bending the sides of the clamping members upwardly and inwardly. The interior side edges of said clamping members 24 have oppositely disposed serrated sections 26 and 27 adapted to engage the sets of teeth 18 and 19 of the locking strip 17.

A series of ice engaging members or nails 28 are adapted to project from the bottom of the clamping members 12 and 13, said members 28 being formed in the shape of inverted square pyramids and having bases fitted within square beveled apertures 29 in the bottom of said clamping members.

The ice-engaging members 28 have sharp points which will be forced into the surface of the ice or other slippery surface under the weight of the wearer.

In operation, when it is desired to assemble the device, the series of pyramid-shaped ice-engaging members 28 will be first inserted with their points downward into the apertures 29 of the clamping members 12 and 13. The clamping members will then be slipped over the body member 23 from the opposite ends thereof until they assume the positions shown in Fig. 1. The locking strip 17 will next be inserted through the slot 16, and the ice creeper will then be placed under the shoe upon which it is to be attached. After the locking strip 17 has been adjusted with relation to the clamping members 13 until the jaws 14 and 15 have come into contact with the sole of the shoe, the operator will rotate the clamping member 19 about its axis by means of the handle 22 from the position shown in full lines of Fig. 1 to the dotted line position in said figure.

In practice, the body member will prefer-

ably be made of sheet metal having sufficient flexibility to permit it to conform to the surface upon which the wearer is walking, whereby a firmer and surer footing on the ground will be obtained.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent is:

1. In an ice creeper, a body member, a pair of shoe-sole clamping members slidable on said body member, and a locking strip for locking said clamping members tightly engaged upon said shoe-sole.

2. In an ice creeper, a body member, a pair of shoe clamping members slidable thereon, a locking strip adjustably secured to one of said clamping members, and a cam member pivoted to said locking strip and engageable with the other clamping member, said cam member having a handle section whereby it may be manually swung from unlocked to locked position.

3. In an ice creeper, a body member, a pair of shoe clamping members slidable thereon, a locking strip adjustably secured to one of said clamping members, and a cam member eccentrically pivoted to said locking strip and engageable with the other clamping member, said cam member having a handle section whereby it may be manually swung from unlocked to locked position.

4. In an ice creeper, a body member, a pair of shoe clamping members slidable thereon, a locking strip adjustably secured to the first clamping member and passing through the second clamping member, and a cam member pivoted to said locking strip and constructed and arranged to engage the second clamping member, said cam member having a handle section whereby it may be manually swung to locked position.

5. In an ice creeper, a body member, a pair of shoe clamping members slidable thereon, ice-engaging means projecting from said shoe clamping members and held in place by said body member, and means for locking said clamping members in engagement with the sole of a shoe.

6. In an ice creeper, a body member, a pair of shoe clamping members slidable thereon, ice-engaging nails projecting from said shoe clamping members and held in place by said body member, and means for locking said clamping members in engagement with the sole of a shoe. 65

7. In an ice creeper, a body member, a pair of shoe clamping members slidable thereon, ice-engaging pointed square nails 70 projecting from said shoe clamping members and held in place by said body member, and means for locking said clamping members in engagement with a shoe-sole.

8. In an ice creeper, a body member, a pair of shoe clamping members adjustably mounted thereon, said shoe clamping members having end jaws for engaging the opposite edges of a shoe-sole, the sides of said shoe clamping members having guiding 80 flanges for said body member, and ice-engaging means projecting from the bottom of said shoe clamping members and held in place by said body member.

9. In an ice creeper, a body member, a pair of shoe clamping members slidable thereon, each of said shoe clamping members having its sides bent over to form guiding flanges for said body member, the guiding flanges of one of said clamping members having oppositely disposed notches, a locking strip resting upon said body member between said notched edges, said strip having a plurality of oppositely disposed teeth fitting said notches, whereby said shoe clamping members may be relatively adjusted to fit various sizes of shoes. 95

10. In an ice creeper, a body member, a pair of shoe clamping members slidable thereon, each of said shoe clamping members having its sides bent over to form guiding flanges for said body member, the guiding flanges of one of said clamping members having oppositely disposed notches, a locking strip resting upon said body member between said notched edges, said strip having a plurality of oppositely disposed teeth fitting said notches, whereby said shoe clamping members may be relatively adjusted to fit various sizes of shoes, and a cam member pivoted to said locking strip at a point outside the free shoe-clamping member, said cam member being constructed and arranged to swing about its pivot to engage said free shoe-clamping member, whereby said clamping members will be forced into locking engagement with the sole of a shoe. 100 110 115

In testimony whereof, I have affixed my signature to this specification.

ROBERT B. FOLEY.
